UNITED STATES PATENT OFFICE.

EUGENE F. TRENT, OF JERSEY CITY, NEW JERSEY.

HEATER.

SPECIFICATION forming part of Letters Patent No. 433,705, dated August 5, 1890.

Application filed March 23, 1889. Serial No. 304,428. (No model.)

To all whom it may concern:

Be it known that I, EUGENE F. TRENT, of Jersey City, in the county of Hudson and State of New Jersey, have invented a certain 5 new and useful Improvement in Heaters, of which the following is a specification.

My improvement relates to heating-drums into which a lamp or burner of any suitable kind may be inserted for the purpose of heating the air within the same and producing a circulation of air through it.

I will describe a heater embodying my improvement in detail, and then point out the novel features in claims.

15 In the accompanying drawings, Figure 1 is a partial side view and partial longitudinal section of a heater embodying my improvement, the section being taken at the plane of the dotted line xx , Fig. 2. Fig. 2 is horizontal 20 section taken at the plane indicated by the dotted line yy , Fig. 1, the lamp which is shown in Fig. 1 being omitted in Fig. 2. Fig. 3 is a horizontal section or view of the drum, taken at the plane of the dotted line zz , Fig. 25 1. Fig. 4 is an inverted plan or bottom view of the drum. Figure 5 is a side view of a drum embodying my improvement employed with a gas-burner, a portion of the drum being broken away or removed to expose the 30 gas-burner and the appurtenances thereof to view. Fig. 6 is a horizontal section taken at the plane of the dotted line ww , Fig. 5.

Similar letters of reference designate corresponding parts in all the figures.

35 Referring first to Figs. 1, 2, 3, and 4, A designates the body of the drum. It is made of cylindric shape in the present example of my improvement. It is preferably made of sheet metal, such as sheet-brass. It is perforated 40 at numerous points. In the present instance it has in the lower portion rows of perforations a' and shortly above these other rows of perforations a^2 . Still higher up it is provided with a row of oblong perforations or 45 slots a^3 . Still higher up it is shown as having another row of oblong perforations or slots a^4 . Higher than these is another row of oblong perforations or slots a^5 , and near the top it will be seen that another row of oblong 50 perforations or slots a^6 exist.

Air is free to enter the rows of perforations a' a^2 . There is no passage for air through

the perforations a^3 , a^4 , or a^5 in the present example of my improvement, because inside the shell opposite these rows of perforations a^3 a^4 55 a^5 , I have fitted strips of mica b^3 b^4 b^5 . These strips of mica are held between bands b , secured inside the shell by solder or any other means. For each strip of mica there are two opposite bands b , and the adjacent edges of 60 the opposite bands are bent inwardly toward the center of the shell and then downwardly, so as to lap over the edges of the mica. This manner of securing the mica may be readily understood by reference to Fig. 1. Air may 65 escape from the upper row of perforations a^6 .

A shell constructed as I have described presents a very tasteful and attractive appearance. Light will shine through the rows of perforations a^3 a^4 a^5 , because, although the 70 mica will prevent the passage of air through these perforations, yet it will permit rays of light to pass through the same.

I have shown the shell as provided with handles a , which may consist of arms of metal 75 secured by rivets or otherwise to the shell, and embracing between them a cylindric roller of wood. These handles serve as a convenient means for lifting and carrying the drum. The drum at the lower portion of its length is 80 provided with a door A' . This door consists of a segment of the drum. It is connected at one edge to the main portion by hinges a^7 , so as to be free to swing laterally, as indicated by the dotted lines in Fig. 2, and provided at 85 the other edge with a catch, here shown as consisting of a rotary pin a^8 , pivotally connected with the door and having affixed to it a hook-shaped catch a^9 , which, when the door is closed, may hook over an arm a^{10} , secured 90 upon the main portion of the drum. This door affords facility for inserting and removing a lamp or burner or any appurtenant part to a lamp or burner. It also affords access to the same while there in place. 95

At the lower end of the drum A there is a flange A^2 . This is shown as having an upwardly-extending rim a^{11} , entering the lower end of the drum. This flange A^2 flares outwardly and has secured to its lower portion 100 a plate A^3 , forming the bottom of the drum. As shown, the outer edges of the plate A^3 are bent downwardly in contact with the inner surface of the lower edge of the flange A^2 and

secured to the latter by any suitable means, in the present instance by small screw-bolts and nuts a^{12} . The drum is shown as supported by legs A⁴, which may be made of cast metal, and have at the upper end horizontally-extending portions which fit against projections a^{13} , with which the bottom plate A³ is provided, these projections being made in a similar manner out of pieces of sheet metal properly bent and attached to the plate. The legs are shown as secured to the projections by screws and bolts a^{14} . It will be observed that the central portion of the bottom plate is depressed downwardly to form a cavity a^{15} , suitable for receiving a lamp or stove C, and that the outer portion of the bottom plate beyond this cavity is provided with perforations a^{16} , through which air may enter and whence it may ascend through the drum. It will also be observed that the flange A² is provided with perforations a^{17} , through which air may enter to the drum.

The lamp or stove C is of the type generally known as a "central-draft lamp," it having an annular wick-tube, an outer air-distributer c' , through which air may pass to the outer surface of the flame, and a central draft-tube c^2 , through which air may ascend to the inner surface of the flame. It will be observed that this lamp is supported by legs C³, which fit in the central cavity a^{15} in the bottom plate of the drum, so that the lamp will be centered.

The bottom plate A³ has a central opening a^{18} , the edges of which are turned upwardly to form a flange or rim. In this flange or rim is telescopically or adjustably fitted a flue D, which may be made of sheet metal and of cylindric form at the lower part and flaring at the upper part. The lamp-reservoir, it will be observed, has in the bottom a central elevation, forming a cavity in the under side. It will be noticed that the central draft-flue starts from this elevation in the bottom of the lamp-reservoir. The flaring upper portion of the flue D fits against the under surface of the central elevation in the bottom of the lamp-reservoir, and hence air which enters the opening a^{18} in the bottom plate of the drum will pass upwardly through the flue and enter the central draft-tube c^2 . Below the central opening a^{18} is a drip-cup E. This is made in the form of a cup having a flat bottom and flaring sides and an upwardly-extending flange at the upper edge. The sides are provided with slots e at a distance above the bottom. The flange at the upper edge is secured to the bottom plate of the drum by clips which overlap the flange and are riveted or otherwise secured to the drum.

G designates a collar. This is shown as composed of two portions, an upper cylindric portion g' and a lower flaring portion g^2 . It is supported by means of brackets or clips g^3 , secured to the drum and extending under the lower edge of the flange-like portion g^2 . This collar is somewhat smaller in circumference

than the drum, so that there may be a passage of air between it and the drum. Extensions g^4 serve to center the collar. The body 70 of the lamp C is some distance below the flange-like portion g^2 , and the burner of the lamp is considerably smaller than the cylindric portion g' . A circulation of air may therefore pass upwardly from the lower portion of the drum around the burner of the lamp. This collar G may be lifted off the brackets g^3 . It may be slipped over the lamp and the lamp may be introduced with it through the door A'. This collar G is an important feature in that it prevents the air from ascending directly upward through the drum and insures a proper amount of air passing to the outer air-distributer c' of the lamp-burner. It keeps the body of the lamp cool 85 by carrying the induced air over the oil-fount and passes it in a heated condition to the top. This collar may be detachable.

At the upper end of the drum A, I have shown an outwardly-extending flange A⁶. 90 The drum has a top plate a^{20} fitted to it. This top plate has a cylindric flange a^{21} . This is secured by bolts and nuts a^{22} to the drum. A⁷ is a removable cover having a lower cylindric portion a^{23} , adapted to fit within the 95 flange a^{21} of the plate a^{20} , and having an upper perforated portion through which air and the products of combustion which may enter the cover can escape. The top plate a^{20} has a central opening a^{24} , the edges of which are 100 here shown as upturned. Beneath this plate a slide or damper a^{25} is arranged. It is secured to one end of a lever a^{26} . This lever is pivoted to the plate a^{20} by a screw a^{27} . The outer end extends through a slot in the drum. 105 By oscillating this lever in one direction the damper a^{25} may be made to cover the opening a^{24} . By oscillating it in another direction the opening a^{24} may be uncovered, so as to allow air and the products of combustion to pass 110 from the drum through the top plate a^{20} . The upper surface of the plate a^{20} is provided with projections a^{28} . Upon these a saucepan or other cooking utensil H may rest. When the damper a^{25} closes the top plate a^{20} , the heated 115 air and products of combustion escape into the apartment in which the drum is arranged from the perforations a^6 .

Turning now to Fig. 5 it will be seen that the drum is the same as that already described. Here I have shown a gas-burner I as used instead of the lamp C, which I have represented in the previous figures. The same collar G is here employed. Gas is supplied to the burner by a pipe J under control of a 120 cock J'.

As shown in Fig. 6, the collar G is composed of two horizontal sections or half-collars, one section of which may be attached to the door of the drum, so as to move outwardly when 125 the door is opened to remove or rearrange the lamp or burner, and the other section is permanently secured to the main portion of the drum.

What I claim as my invention, and desire to secure by Letters Patent, is—

1. The combination, with a perforated drum having a damper in its top plate and a central-draft lamp communicating with a central flue rising from an opening in the bottom of the drum, of a collar consisting of a flaring lower portion and a cylindric upper portion, the said collar being removable and surrounding the burner and diverting air ascending through the drum to the burner, substantially as specified.

2. A heating-drum made of sheet metal and perforated at various points throughout its length, the perforations between the upper and lower portions being backed with mica, a slide or damper in a top plate, and the drum having a segment separated from the main portion and connected thereto by hinges to form a door, substantially as specified.

3. The combination, with a drum fitted to receive a central-draft lamp, of an adjustable central flue rising from an opening in the bottom of the drum and adapted to communicate with the central tube of the lamp, substantially as specified.

4. The combination, with a drum fitted to receive a burner and having a door, of a collar comprising two sections or parts and having one part secured to the main part of the drum and the other part secured to the door, the said collar serving to direct air ascending

through the drum to the burner, substantially as specified.

5. The combination, with a drum fitted to receive a central-draft lamp, of a central flue rising from an opening in the bottom of the drum and adapted to communicate with the central tube of the lamp, and a drip-cup fitted below the said flue and having openings in the sides, substantially as specified.

6. The combination, with a drum fitted to receive a central-draft lamp, of a central flue rising from an opening in the bottom of the drum and adapted to communicate with the central tube of the lamp, said flue having a cylindric lower portion and a flaring upper portion, substantially as specified.

7. The combination, with a drum constructed to receive a lamp, of a bottom plate having a central depression or cavity for supporting and centering the lamp, and a central draft-flue opening, substantially as specified.

8. The combination, with a drum, of a burner arranged within the drum, and a collar located within the drum, surrounding the lower portion of the burner and directing air ascending through the lower portion of the drum to the lower portion of the burner, substantially as specified.
